[57] **CLAIM**

The ornamental design for an electrode for a plasma arc torch, as shown and described.

DESCRIPTION

FIG. 1 is a top perspective view of an electrode for a plasma arc torch embodying the design of the invention;
FIG. 2 is a side elevational view of the electrode of FIG. 1;
FIG. 3 is a top view of the electrode of FIG. 1;
FIG. 4 is a bottom view of the electrode of FIG. 1; and,
FIG. 5 is a bottom perspective view of the electrode of FIG. 1.
